Primary Examiner — Cynthia M. Chin(74) *Attorney, Agent, or Firm* — Daryl R. Wright; Greg Carr(57) **CLAIM**

I claim the ornamental design for a wheel for a model vehicle, as shown and described.

DESCRIPTION

FIG. 1 is an upper, left, front perspective view of a wheel for a model vehicle;

FIG. 2 is a left elevation view thereof;

FIG. 3 is a right elevation view thereof;

FIG. 4 is a rear elevation view thereof; and,

FIG. 5 is an upper, left, front perspective environmental use view.

In the drawings, the broken line showing of features of the wheel for a model vehicle illustrate portions of the wheel for a model vehicle that form no part of the claimed design; whereas, the broken line showing of the environmental use view depicts environmental subject matter and is provided for the purposes of illustrating environmental use structure and context and forms no part of the claimed design.
